TOY ELECTRIC RAILWAY CAR

Robert Louis F. McDonald, Rochester, N. Y., assignor to R. L. McDonald Company, Rochester, N. Y., a firm

Application September 6, 1947, Serial No. 772,519

7 Claims. (Cl. 46—217)

1

The present invention relates to toys and to electric motors therefor, and in particular to toy railway cars and to electric motors such as are adapted to be employed in propelling such cars on toy electric train tracks.

The primary object of this invention is to construct an electric motor suitable for use in the cars of toy trains which will be extremely simple in structure and contain as few parts as possible.

Another object of the invention is to provide a simple electric motor which will be set in motion by movement of the car in which it is mounted, and which will continue in motion, driving that car, until the car itself is stopped.

Still another object of the invention is to provide a toy hand car for toy railways, which in operation will closely simulate a hand car, such as used on standard railway systems, and yet which will be simple in construction and of relatively low cost.

Other objects of the invention will be apparent hereinafter from the specification and from the recital of the appended claims.

In the drawings:

Fig. 1 is a vertical sectional view through a toy hand car constructed according to this invention showing particularly the motor for powering the same, the car being shown mounted on the tracks of a toy railway system;

Fig. 2 is an end view of the car, looking at the front end of the car, parts being broken away to show the motor and the driving wheels;

Fig. 3 is a side elevation of a car made according to a modification of the invention;

Fig. 4 is a view looking at the front end of this car;

Fig. 5 is a side elevation, with parts broken away, showing a still further modified form of car;

Fig. 6 is a diagrammatic view illustrating the construction and operation of the motor and showing how it may be wired for a three rail electric train system; and

Fig. 7 is a similar diagrammatic view showing how the motor and car may be wired for a two rail electric train system.

A motor constructed according to the present invention comprises simply a field magnet consisting of a field coil and a soft iron core, a soft iron armature or rotor which turns with the wheels of the car between the poles of the field magnet, and means for intermittently deriving current for the field coil from the track on which the unit is running. In a three rail system, the last-named means comprises a sliding or rolling contact member which engages the third rail, and which is connected to one side of the field coil, and one pair of the car wheels, this pair of car wheels being constructed to derive cur-

2

rent intermittently from the other two rails of the system and being connected directly to the armature or rotor. In the three rail system, the shaft, which carries the rotor and these two wheels, is journaled directly in the metallic frame of the car, and the other side of the field coil is grounded to the car frame.

In a two rail system, one side of the field coil may be connected to a conducting wheel that runs on one track, and the other side of the field coil may be connected to the axle which carries the rotor and a wheel that is constructed to derive current intermittently from the other track. In this case, the frame of the car is insulated from the wheels, and the two other wheels of the car are insulated from the tracks on which they run.

Referring now to the drawings by numerals of reference, and particularly to Figs. 1 and 2 first, 20 10 denotes the body or frame of a simple form of toy hand car constructed according to one embodiment of this invention. This is made of metal such as steel and is of U-shape in cross-section. The car is mounted to run on two pairs 25 of wheels, the front or driving wheels of the car being designated at 14 and 15 and the rear or non-driving wheels at 16 and 17. The driving wheels 14 and 15 are secured to an axle 18 which is journaled directly in the sides or skirts 30 of the U-shaped frame 10. The non-driving wheels 16 and 17 are secured to an axle 19 which is insulated from the frame of the car by a sleeve 39 which may be made of any suitable insulating material.

35 The wheels 14 and 16 of the car are adapted to roll on one rail 30 of the track, and the wheels 15 and 17 on another rail 31 thereof. Between the two rails 30 and 31 is the rail 32 which constitutes the third rail of the system. A shoe 35 rides on the third rail. The two rails 30 and 31 may be connected to one terminal of the transformer used with the electric train system, while the third rail is connected to the other terminal of this transformer. The wheels 14 and 40 15 are made of insulating material 28, but each has a copper shoe or segment 29 embedded therein and extending diametrically thereacross, so that as these wheels revolve, the alternating conducting and insulating segments of the wheel tread intermittently make and break contact with the rails 30 and 31 on which they roll, respectively.

45 Welded or soldered to the underside of the body portion of the frame 10 of the car is the iron core 25 of a horseshoe type field magnet. The field coil of this magnet is designated at 26. It is wound around one leg of the core. The field coil is connected on one side by line 37 (Fig. 6) with the axle 18; it is connected on the

other side to shoe 35 which rides on third rail 32. 27 denotes an armature or rotor which is secured to the axle 18, to revolve between the poles of the core 25 and cut the lines of force, which flow between these poles, as the wheels 14 and 15 revolve.

To start the car, it must be given a slight push manually, but when it has once started rolling, the motor will drive it, as long as current is supplied to the rails 30, 31 and 32, until it is manually stopped, or positively stopped in some other fashion. The rotor 27 and blocks 29 act in effect as a commutator and the momentum of the car itself will carry the rotor or commutator over gaps in the rails or switches. The commutator being integral with the driving wheels of the car derives current intermittently from the track on which the car is running.

The motor of the present invention may be used to drive any type of toy which does not constitute too heavy a load for the motor. Toy hand cars are especially suited to be driven by a motor such as described. These hand cars may, of course, have different constructions. The hand car shown in Figs. 1 and 2 is of the simplest design. Besides the parts already described, it comprises simply two U-shaped wire rods 11 and 12 which are soldered or otherwise fastened to the skirts of frame 10 at the front and rear thereof, and which simulate front and rear hand rails or guards.

A more elaborate form of hand car is shown in Figs. 3 and 4. Here essentially the same U-shaped sheet metal frame 40 may be used as the frame 10. To the rear of this figure there is secured a U-shaped reinforcing rod 42, and to the front of this frame there is secured a U-shaped rod 41 which is bent slightly rearwardly near its top or bight portion and which has mounted between its legs above the frame 40 a windshield 45. This is provided with window openings 46 to simulate a standard motor-driven hand car. It is also provided with a pair of openings which emit light from one or more light bulbs 48, simulating the headlights of such a hand car. These bulbs are mounted in an angular bracket 47 and may be connected in circuit with the coil 26 by lines 49 and 50 as shown diagrammatically in Fig. 6. They will flicker on and off because of the intermittent making and breaking of the circuit to the coil 26, but will suffice for the purpose. A U-shaped cover piece 48', attached to the upper face of frame 40, may be provided to enclose bracket 47 and bulbs 48.

Another way in which the hand car may be constructed is shown in Fig. 5. Here the frame 60 is essentially of the same U-shape construction as the frame 10, but mounted on the frame is a post 61 upon which is pivotally mounted at 62 a lever 63. This lever is pivotally connected at 64 to a rod 65 which is secured to an offset throw portion of a shaft 66 to which wheels 16 and 17 are fastened. This shaft takes the place of shaft 19 of the previously described embodiments of the invention. Mounted also on the frame 60 is a figure 70 simulating a man. This figure may have one or two legs 71 pivotally connected at 72 to a lug on the frame 60 and pivotally connected at 73 to the body portion of the figure; and may have one or two arms 75 pivotally connected at 76 to the body of the figure and pivotally connected at 77 to lever 63. As the car rolls along, then, the man will move up and down as though he were operating the lever 63. Two different positions of the man, lever, 75

and link are shown in full and dotted lines in Fig. 5.

When the hand car is to be used in a two-rail system, the basic construction is preserved but a somewhat different way of transmitting current to the field coil is used. This is shown diagrammatically in Fig. 7.

Here the frame of the car is insulated from the wheels in any suitable manner. One driving wheel 84 of the car is made of an insulating material and the other driving wheel 85 is built like the wheels 14 and 15; it is made of a plastic insulating material 80 and has a block 81 of copper or other conducting material molded into it. The block 81 extends diametrically across the wheel 80 and is adapted to make current conducting contact intermittently with the rail on which the wheel runs, as the wheel revolves thereon. The two wheels are secured to a shaft 83 upon which is mounted the armature or rotor block 90. One of the two non-driving wheels is a conducting wheel. This wheel is at the opposite side of the car from wheel 85 and is adapted to roll on the other track of the system. It may be made of copper, steel or other conducting metal. The other non-driving wheel 87 is a non-conducting wheel made of insulating material. The two non-driving wheels are secured to a shaft 89. This shaft is connected by a line 91 with one side of a field coil 95 and the other side of this field coil is connected by a line 92 with the shaft 88. The field coil is wound around a soft iron magnet such as the magnet core 25 of Fig. 1 and the rotor 90 is adapted to revolve between the poles of this magnet. Thus, as the car moves along the tracks 96 and 97 which are connected to a transformer or other suitable source of power and to the positive and negative terminals thereof, respectively, the wheel 86 picks up current from the track 96 which is transmitted through the line 91, coil 95, line 92, shaft 88 and intermittently through the block 81 to the rail 97, intermittently completing a circuit. Thus the coil 95 is intermittently energized. As the car runs along, moreover, the rotating armature 90 intermittently cuts the lines of force between the poles of the magnets, so long as there is current in the tracks 96 and 97. Thus, when a car has been started it will run until stopped. If it is desired to have lights on the car, these lights, such as the lights 100, may be connected with the lines 91 and 92 respectively by lines 101 and 102 respectively.

While the invention has been described in connection with different embodiments thereof, it will be understood that it is capable of further modification and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. A wheeled car for a toy electric railway comprising a frame, wheels on which the frame is mounted and which are adapted to roll on parallel rails of said railway, a field magnet mounted on the frame, a field coil wound around said magnet, an armature connected with one of the wheels to rotate therewith and positioned to re-

volve between the poles of the magnet, one of said wheels being constructed to make intermittent electrical contact only, as it revolves, with one of the rails of said railway, means for electrically connecting said one wheel to one side of the field coil, and means adapted to connect the other side of the field coil electrically with another rail of said railway as the toy moves along said railway.

2. A wheeled car for use on a toy electric railway three-rail system, comprising a frame, wheels on which the frame is mounted and which are adapted to run on two rails of said system, a field magnet mounted on the frame, a field coil wound around said magnet, an armature connected with one of the wheels to rotate therewith and positioned to revolve between the poles of the magnet, one of the wheels being made of an insulating material but having a block of conducting material embedded therein which extends part-way only around the periphery of the wheel so as to make intermittent contact only with the rail on which said one wheel runs as said one wheel revolves thereon, means for electrically connecting said one wheel to one side of the field coil, and means adapted to ride on the third rail of said system to connect said rail electrically with the other side of the field coil.

3. A wheeled car for use on a toy electric railway three-rail system, comprising a frame made of an electrical conducting material, a pair of axles journaled in the frame, a pair of wheels secured to each axle, one pair of wheels being made of an insulating material to be insulated from the rails on which they may run, means for insulating the axle, to which said one pair of wheels is secured, from the frame, the other pair of wheels being made of insulating material but each having an electrical conducting block embedded therein which extends part-way only around the periphery of each of the latter pair of wheels so as to make intermittent electrical contact with the rails on which said other pair of wheels run as the wheels revolve, a field magnet mounted on the frame, a field coil wound around said magnet, an armature mounted on the axle of said other pair of wheels, said armature being made of an oblong block of iron, which is of greater width than thickness, and being positioned to revolve between the poles of the magnet, one end of the coil being grounded to the frame, and means connected electrically to the other side of the coil and adapted to ride on the third rail of the system.

4. A wheeled car for use on a toy electric railway two-rail system, comprising a frame, wheels on which the frame is mounted and which are adapted to run on the rails of said system, a field magnet mounted on the frame, a field coil wound around said magnet, an armature connected with one of the wheels to rotate therewith and positioned to revolve between the poles of the magnet, one of the wheels being made of an electrically conducting material and being electrically connected to one side of the coil, and another of the wheels being made of an insulating material but having an electrical conducting material embedded therein that extends part-way only around the periphery of the last-named wheel so as to make intermittent contact with the rail on which the last-named wheel runs as the last-named wheel revolves, and means electrically con-

necting the last-named wheel with the other side of the coil, said two named wheels being insulated from each other and being mounted at opposite sides of the car to run on separate rails.

5. A wheeled car for use on a toy electric railway two-rail system, comprising a frame, a pair of axles journaled in the frame, a pair of wheels secured to each axle, one wheel of one pair being made of an electrically conducting material and one wheel of the other pair being made of an insulating material having an electrically conducting block embedded therein and extending diametrically thereacross so as to make contact intermittently only with the rail on which said one wheel runs as said one wheel revolves, said two named wheels being disposed at opposite sides of the car to roll on separate rails, the other two wheels being made of insulating material, a field magnet mounted on the frame, a field coil wound around said magnet, an armature connected with the second named wheel to revolve therewith and positioned to revolve between the poles of said magnet, and means electrically connecting the two axles with opposite sides of the coil.

6. A wheeled toy for use on an electrified railway system comprising a frame, a plurality of pairs of wheels on which the frame is mounted and which are adapted to roll on the electrified rails of said system, a field magnet mounted on the frame, a field coil wound around said magnet, and an armature connected to one pair of said wheels to rotate therewith and positioned to revolve between the poles of said magnet, at least one of said one pair of wheels being constructed to make intermittent electrical contact with the electrified rail on which it runs as it rotates, thereby producing intermittent surges of current through the field coil to cause rotation of the armature and said one pair of wheels, and means including said one wheel for transmitting current intermittently to said field coil from the rails.

7. A wheeled car for a toy electric railway having at least two parallel rails through which operating current is supplied, said car comprising a frame, a plurality of wheels on which said frame is mounted, a field magnet mounted on the frame, a field coil wound around said magnet, an armature connected with one of said wheels to rotate therewith and positioned to revolve between the poles of said magnet, electrically-conducting means connected electrically to one side of said field coil and connected to one of said wheels to rotate therewith and to engage intermittently one of said two rails of said railway as the wheels rotate, whereby to connect one side of said field coil intermittently with the operating current, and means adapted to engage the other of said two parallel rails for electrically connecting said last named rail continuously to the other side of said field coil as the wheels rotate.
